Inventor,
Joseph A. Hoegger,
By his Attorney,
Hoegger & Neary

UNITED STATES PATENT OFFICE

JOSEPH A. HOEGGER, OF JERSEY CITY, NEW JERSEY

BRACKET AND SHELF

Application filed October 4, 1927. Serial No. 223,871.

My invention relates to improvements in shelf supporting brackets and the combination between a shelf and a bracket. My invention relates more particularly to brackets and shelves which are of an ornamental nature and in which it is desirable to have the shelf firmly supported, but in such a way that it may be removed readily when desired.

10 The invention is further intended to produce a simple, useful and handsome structure.

The invention is also especially applicable for use in connection with a glass shelf which 15 is supported by the bracket in such a way that the edges of the shelf are grasped between complementary abutments of the bracket arm so that the shelf is held against displacement, but one member of the bracket arm is movable 20 against a strong tension, however, so that when desired the shelf can be removed.

Reference is to be had to the accompanying drawings forming a part of this specification, in which similar reference characters 25 refer to similar parts throughout the several views.

Fig. 1 is a front elevation of a shelf and supporting bracket arms embodying my invention.

30 Fig. 2 is a vertical section on the line 2—2 of Fig. 3.

Fig. 3 is a longitudinal section on the line 3—3 of Fig. 2; and

Fig. 4 is a detail of parts of the apparatus.

35 The shelf 10 while it may be of any desired material is usually of glass as my whole structure is intended primarily to be ornamental and a glass shelf lends itself to this idea. The shelf has beveled edges and it is supported on

40 the bracket arms 12. Each of these arms has an horizontally extending portion 13 to carry the shelf and base 14 which is intended to abut with the supporting wall or the like. In the drawing I have shown the base recessed as at 15 and the arm provided near its base

45 with a socket 16, with the idea of providing a support in accordance with the disclosure of my application for Letters Patent of the United States, Serial No. 619,549, filed February 17, 1923. In such case the supporting

stem enters the socket 16 and the member 13 is fastened by a set screw 17. However, so far as this particular invention is concerned the bracket arm 13 can be supported in any preferred way without affecting the novel 55 features of the structure.

On the upper side the bracket arm has near the base and near the outer end beveled abutments 18 and 19, which are complementary to the beveled edges 11 of the shelf 10 and which are arranged so as to grasp the shelf edges and prevent the accidental displacement of the shelf, as clearly shown in Fig. 2. The abutment 19 is formed on the face of the lug or hook 20 which has a shank 21 slidably in and out in the bore 22 at the outer end of the bracket arm 13. This shank 21 has at its end extensions 23 (see Fig. 4) which enter a guide slot 24 in the abutment and a guide 25. This is a cylindrical member screw threaded to engage the internal thread in the bore 22, so that by screwing the member 25 to its seat it forms a support and guide for the pull-rod 27 attached to the shelf 21 and an abutment for the spring 30 presently referred to. The guides 23 prevent the shank 21 and the lug 20 from turning. The member 25 has a bore 26 extending longitudinally through it and the guide rod and pull rod extend through this bore and the outer end of the rod is threaded in the shank 21 as shown at 28 in Fig. 2. The inner end of the rod 27 lies in a reduced part 22' of the bore 22 and has a head or collar 29 between which and the abutment and guide 25 is a stiff coil spring 30 which is wound around the rod. Thus, it will be seen that the pressure of the spring 30 pulls the rod 27 and the shank 21 inward, so that the abutting face 19 of the lug 20 is in constant and firm contact with the edge 11 of the shelf 10, but if it is desired to remove the shelf the member 21 can be pulled out against the tension of the spring 30 so as to free the shelf edge and permit the easy removal of the shelf. It will be noted that the arrangement for maintaining the hold or spring contact is entirely concealed, is simple in structure so that it will not get out of order and that it holds the lug 20 in such

30 35 40 45 50 55 60 65 70 75 80 85 90 95 100

a manner as to prevent it from turning out of contact with the shelf edge.

It will be further noted that the particular structure for guiding and horizontally supporting the engaging member 20 of the bracket can be changed without affecting the principle of the invention.

I claim:

1. A shelf supporting bracket adapted to be secured to a wall, comprising a horizontally projecting shelf supporting arm, means carried by said arm adjacent said wall adapted to grip the edge of a shelf resting thereon, said arm having a hole longitudinally entering at the extremity thereof remote from said wall, an internal thread in the said hole, an externally threaded plug adapted to be threaded into the said hole, a rod slidably carried in the said plug, a spring abutment at the end of said rod, a spring intermediate said abutment and said plug, means adapted to grip the outer edge of a shelf resting on said projecting arm, rigidly connected to a guide piece adapted to reciprocate in the said hole and rigidly secured to the said rod whereby the said gripping means is firmly held against the edge of said shelf and may be manually retracted from contact therewith when removal of the shelf is desired.
2. Apparatus according to claim 1 in which the guide piece for said gripping means carries projecting pins which mesh with recesses in the said plug whereby the said guide piece, plug and tensioning means may be threaded into operative position.
3. A shelf supporting bracket comprising an arm having means for rigid attachment to a wall, said arm having a fixed external shelf engaging abutment and an internal bore at its outer edge, an extensible element adjustable within the aforesaid bore comprising a lug with a shelf engaging abutment thereon, a plug in which the lug has a guided movement, and a spring disposed to draw the said lug into the said bore.
4. A shelf supporting bracket comprising an arm having means for rigid attachment to a wall said arm having an external shelf engaging abutment thereon and a bore at its outer end, a lug slidable in the bore of the arm and having a shelf engaging abutment thereon, a plug adjustably secured in the bore of the arm, guide members connected to the lug and fitting the complementary part of the plug, and a spring pressed rod extending through the plug and connected to the aforesaid lug.

In testimony whereof, I have signed my name to this specification this 3d day of October, 1927.

JOSEPH A. HOEGGER.
